PULL TOY

Walter P. Doe, East Aurora, N.Y., assignor to The
Quaker Oats Company, Chicago, Ill.

Filed Feb. 22, 1971, Ser. No. 117,847

Term of patent 14 years

Int. Cl. D21—01

U.S. Cl. D34—15

FIG. 1

FIG. 2

FIG. 5

FIG. 1 is a front perspective view of a pull toy showing my new design;

FIG. 2 is a front elevation thereof with the bellows member and the connecting tube broken away for purposes of clarity;

FIG. 3 is a side elevation thereof as viewed from the left in FIG. 1 with the bellows positioned in front of the toy as in FIG. 5, for purposes of illustration only;

FIG. 4 is a rear elevation thereof; and

FIG. 5 is a top plan view thereof with the bellows member positioned in front of the toy as in FIG. 3.

I claim:

The ornamental design for a pull toy, substantially as shown and described
